UNITED STATES PATENT OFFICE.

HUGH PRENTICE, OF BELLEVUE, PENNSYLVANIA.

REGENERATOR SYSTEM FOR BY-PRODUCT COKE-OVENs.

No. 926,647.

Specification of Letters Patent.

Patented May 4, 1909.

Application filed March 7, 1908. Serial No. 419,708.

To all whom it may concern:

Be it known that I, HUGH PRENTICE, a citizen of the United States, residing at Bellevue, in the county of Allegheny and State of Pennsylvania, have invented certain new and useful Improvements in Regenerator Systems for By-Product Coke-Ovens, and do declare that the following is a full, clear, and exact description of the invention, which will enable others skilled in the art to which it appertains to make and use the same.

My invention relates to an improved regenerator system for by-product coke ovens, and the object of the invention is to provide an oven which, among other things, contains a means for supplying a continuous quantity of heated air to the fuel burners therein, and obviating the necessity of reversing the hot gases in the combustion chambers of such ovens, as is now commonly done, thus making a continuous heating oven and considerably increasing the efficiency and capacity of the oven, all as hereinafter fully described and particularly pointed out in the claims.

In the accompanying drawings, Figure 1 is a vertical sectional elevation longitudinally of one end or half of a coke oven and my improved regenerator therefor, being broken away at the left and which omitted part is an exact duplicate of that shown excepting that it is reversed and arranged back to back thereto. This view is taken on line 1—1, Figs. 2 and 4 and shows a combustion chamber and a regenerator chamber in open communication therewith and with its valves arranged to permit the escape of waste gases to the offheat flue leading to the stack. Fig. 2 is a cross section corresponding to line 2—2, Fig. 1 of one complete oven or coke-chamber with a pair of regenerator chambers below, said view representing only what may be considered one unit in a series of similar units which are combined in any desired number. Fig. 3 is a vertical sectional elevation centrally of the coke chamber and through a regenerator chamber which is taking in air to supply the combustion chambers and being on line 3—3, Figs. 2 and 4 of the regenerator next adjacent to the one shown in Fig. 1. Fig. 4 is a vertical cross sectional view corresponding to line 4—4, Fig. 3 and serving particularly to disclose the respective flues and passages crossed on that line.

The drawings as thus described show my

improved system as applied to a horizontal type of oven and which is the preferred construction, but it is likewise applicable to the vertical flue type of oven by slight modification of the air flues to the burners. In Fig. 1, the sectional view shown discloses the regenerator discharging the hot waste gases from the combustion chambers, and Fig. 3 shows the regenerator next adjacent to that of Fig. 1, taking in air to supply the combustion chambers.

The broad idea herein is to maintain constant combustion in the combustion chambers of the oven and at the same time utilize the hot waste gases from the combustion chambers to continuously heat the air supply passing to said combustion chambers, and all without reversing the hot gases in the combustion chambers as now practiced, but by a reversal of the waste gases in the regenerators alone, thus saving in the quantity of gas required in coking of coal as well as making a continuous heating oven.

In my system as thus shown I employ a series of regenerator chambers or regenerators indicated by C and C' respectively, arranged in pairs at each end or half of each coke chamber or oven A', so that when air is passing through one in one direction, hot waste products are passing out through the other in the opposite direction, the same being adapted to alternate in this respect, first, to store up the heat of the waste gases, and second, to heat the air for combustion purposes when reversal is effected. To this end, air enters regenerator C from the outside in Fig. 3, as indicated by open air passage a wherein valve H is closed as to the offheat flue S leading to a stack (not shown), while in Fig. 1 the said passage is closed for the regenerator C' next adjoining by valve H' and the exit to the stack is open for the products of combustion coming back through regenerator C', and heating the check-work built-in open work and walls of said passages as said waste products pass to the stack. Thus I store the said regenerator chambers C and C' alternately with heat and then absorb the stored heat in the air that flows reversely through the same flues onward to combustion chambers D of the oven to supply combustion. In reality, each oven A' has four regenerator chambers arranged with two chambers underneath each end of the oven, the drawings only showing one half, or in other words, one side of a system.

Valves H and H' each control both the air inlet a and the exit 4 for their respective regenerators and valve G and G' likewise control both the hot air inlet E from their respective regenerators to combustion chambers D and the waste outlet B. Any suitable form of valve may be used and they may be operated by any suitable means. Separate valves may be employed for openings B and E and a and 4, respectively, instead of a single double acting valve as shown.

The waste gases or products leave the combustion chambers D, one at each side of the oven or coke chamber A', and enter into a centrally located circuitous passage A² which opens into a horizontal passage A³ running transversely of the oven and common to all in the series, and exit of these gases is through openings B to each regenerator, say C' when the valve therefor is open. From thence, the gases run back and forth to the exit 4 at the bottom. During this time, the air is passing in opposite direction through regenerator C and out at opening E to horizontal air flue F across the front of the oven from which it is supplied to the combustion chambers D and the burners D' by vertical flues F' and ports K at the side thereof. By moving the slide dampers G and G' and H and H' the air and gases are reversed from one regenerator to the other of a set, and by means of horizontal passage or waste gas cross flue A³ and the hot air cross flue F, a flexible arrangement is obtained, whereby two or more ovens can work on one set of regenerators, if desired.

Suitable doors are provided for each end of the oven as usual although not shown, and it will be understood that the construction of the oven is otherwise as ordinary, and is supplied with all the other necessary details and parts to make it complete and practical.

What I claim is:—

1. In by-product coke ovens, a series of ovens having a double regenerator beneath each half thereof and provided with com-

bustion chambers having both waste product and air intake passages connecting all said combustion chambers and said regenerators; and means to control the direction of flow to said regenerators to and from said passages, and whereby continuous heating of the said ovens is obtained with a reversal of flow in the regenerators only. 55

2. In a regenerator system for coke ovens, a bank of ovens, each having combustion chambers provided with discharge passages for the products of combustion and air intake passages for the burners, and a plurality of regenerator chambers for each oven having separate valved intakes and outlets adapted to reverse the flow of waste products and air alternately from one regenerator chamber to another without reversing the flow of waste products or air within the combustion chambers. 60

3. In a regenerator system for by-product coke ovens, the ovens and burners therefor having the return flue regenerator chambers for heating the air supply by the waste products comprising a series of such chambers to each oven arranged in pairs, and provided with means to reverse the flow of said waste products and air alternately through pairs of said chambers and thereby maintain a continuous flow of heated air to said burners. 70

4. A series of coke ovens arranged side by side and having combustion chambers between them and a cross discharge flue connected with said combustion chambers, and separate air flues to said combustion chambers having an inlet cross passage connected with said air flues, in combination with regenerators arranged in pairs and opening into both said cross discharge flue and inlet cross passage and having valved means to open and close the same separately. 80

In testimony whereof I sign this specification in the presence of two witnesses.

HUGH PRENTICE.
